OUTRIGGER CANOE

Arnold H. Eschmann, 6019 Camelia, Houston, Tex.

Filed Sept. 20, 1963, Ser. No. 76,655

Term of patent 14 years

(Cl. D71—1)

FIG. 1 is a side elevational view of an outrigger canoe, showing my new design;

FIG. 2 is a perspective view thereof; and

FIG. 3 is a front elevational view thereof.

Portions are omitted in FIGS. 2 and 3 for clarity of illustration. The side not shown is substantially the same as the side shown.

I claim:

The ornamental design for an outrigger canoe, as shown and described.
